MARTIN CHRISTIANSEN, OF NEW YORK, N. Y.

COMBINATION HAIR BRUSH AND COMB.

1,196,522.

Specification of Letters Patent. Patented Aug. 29, 1916.

Application filed January 27, 1916. Serial No. 74,630.

To all whom it may concern:

Be it known that I, MARTIN CHRISTIANSEN, a subject of the King of Norway, and a resident of the city of New York, borough 5 of Bronx, in the county of Bronx and State of New York, have invented a new and Improved Combination Hair Brush and Comb, of which the following is a full, clear, and exact description.

10 My invention relates to a combination hairbrush and comb, in which the comb is detachable from the brush and, therefore, each may be used separately.

An object of the invention is to provide a 15 simple, convenient and inexpensive article in which the comb is located between the bristles of the brush.

A further object of the invention is to provide an article of the class described in 20 which the comb is automatically placed obliquely to the brush when the article is used, thus rendering the use of the article more agreeable and efficient.

With the above and other objects in view, 25 the nature of which will more fully appear as the description proceeds, the invention consists in the novel construction, combination and arrangement of parts as herein fully described, illustrated and claimed.

30 In the accompanying drawings, forming part of the application, similar characters of reference indicate corresponding parts in all the views.

Figure 1 is a perspective view of an embodiment of my invention; Fig. 2 is a longitudinal section on line 2—2, Fig. 1; and Fig. 3 is a transverse section on line 3—3, Fig. 1.

The back 4 of the hairbrush is provided 40 with a longitudinal, substantially central slot 5. The sides of the slot taper downwardly, so that the slot is wider at the upper surface of the back than at the lower surface thereof. The slot at the lower surface is evenly spaced from the adjacent rows 45 of bristles 6.

Fitting into the slot 5 is a comb 7, the teeth 8 of which project through the slot to lie between the rows of bristles. The comb 50 has alining projections 9 at the back thereof. Said projections are rounded and are mounted to roll on bearing surfaces 10 which are depressed from the upper surface of the brush back in the ends of the slot 5.

55 The comb 7 is retained in the slot on its bearing surfaces by a fastener or latch 11

of any suitable resilient material. The latch is preferably hinged to the back so that the comb may be removed when it is desirable to use the brush without the comb or the 60 comb without the brush, or for any other purpose, as for exchanging a comb, or otherwise. The fastener 11 has a depressed portion 12 which yieldingly maintains the back of the comb against either of the sloping 65 sides of the slot 5. The resiliency of the portion 12 of the fastener 11 is such as to yield when the comb engages the hair and the brush is moved in the direction of the arrow α , as shown in Fig. 3. This change 70 of position of the comb in the brush renders the article more agreeable to use. It will be noted that the tendency of the comb is always to make an obtuse angle with the direction of motion of the brush. It is 75 self-evident that the fastener 12 may be made stiff enough to resist an automatic change of position of the comb in the brush.

I claim:

1. In an article of the class described, a 80 brush the back of which has a longitudinal, substantially central slot the sides of which taper so that the slot is wider at the upper surface than at the lower surface of the back, said slot being adapted to admit a 85 comb therethrough from the back, bearing surfaces at the ends of the slot depressed from the upper surface of the back and adapted to engage the ends of the comb inserted into the slot, and resilient means to 90 retain yieldingly the comb at either side of the slot.

2. In an article of the class described, a brush the back of which has a longitudinal slot closed at the ends and tapering downwardly, said slot being adapted to receive a comb from the back of the brush, bearings on the ends of the slot, and means adapted to retain the comb in the slot on the bearings and retain the comb yieldingly against 100 either side of the slot.

3. In an article of the class described, a brush the back of which has a slot tapering downwardly to receive a comb so that the teeth of the comb will be located between 105 the rows of bristles of the brush, said brush presenting bearings in said slot for the ends of a comb engaged in the slot, and means for maintaining a comb in the slot on the bearings and yieldingly retain the comb 110 against either side of the slot.

4. In an article of the class described, a

- brush the back of which has a longitudinal slot the sides of which taper so that the slot is wider at the upper surface than at the lower surface of the back, said slot having 5 bearing surfaces at the ends thereof, and resilient means secured to the back across the slot and adapted to engage the back of a comb engaged in the slot.
5. In an article of the class described, a 10 brush having a longitudinal slot closed at the ends and tapering downwardly to receive a comb therein, and means adapted to engage the back of the comb to lock the comb in the slot.
6. In an article of the class described, a 15 brush the back of which has a longitudinal slot closed at the ends to receive a comb through the back of the brush, and means extending across the slot adapted to engage the back of the comb and lock the comb in 20 the slot.

In testimony whereof I have signed my name to this specification in the presence of two subscribing witnesses.

MARTIN CHRISTIANSEN.
